UNITED STATES PATENT OFFICE.

ALBERT E. FISH, OF DENVER, COLORADO, ASSIGNOR TO GLEN D. HARRINGTON, OF DENVER, COLORADO.

CONCENTRATOR-TABLE.

1,319,383.

Specification of Letters Patent. Patented Oct. 21, 1919.

Application filed November 11, 1916. Serial No. 130,886.

To all whom it may concern:

Be it known that I, ALBERT E. FISH, citizen of the United States, residing at the city and county of Denver and State of Colorado, have invented certain new and useful Improvements in Concentrator-Tables; and I do declare the following to be a full, clear, and exact description of the invention, such as will enable others skilled in the art to which it appertains to make and use the same, reference being had to the accompanying drawings, and to the characters of reference marked thereon, which form a part of this specification.

15 The present invention relates to improvements in concentrators for separating mineral from the pulverized rock or sand in which it may be contained and the main object of the invention is to accomplish such 20 separation in a more rapid, efficient and economical manner than has been done heretofore.

The invention relates to concentrators of the class wherein a table is mounted to oscillate longitudinally in such a manner as to cause the concentrates to travel toward the tail of the table, or the extremity opposite the head where the material to be treated is fed thereto; while the gangue travels in a transverse direction, being discharged at the lower longitudinal edge of the table, which is inclined both longitudinally and transversely.

35 The material to be treated, in the form of pulp, is discharged at the upper or highest corner of the head of the table while the wash water utilized in treating the material is delivered to a trough arranged along the upper longitudinal edge of the table, one 40 wall of the trough being perforated to permit the escape of the water to the concentrating surface of the table top.

An important feature of the present invention which makes the apparatus more efficient in the handling of heavy clay and sticky substances which tend to clog and "freeze" on the table, is the provision of a series of agitators adapted to be positioned to operate on the material between the riffles. 50 These agitators are in themselves stationary but they are mounted in such manner as to extend downwardly between the riffles which latter, together with the table on which they are carried, reciprocate rapidly in relation 55 to the agitators. In order to use such agita-

tors practically it is essential that they be carried on adjustable mountings to meet the varying angular positions of the table.

The particular formation and arrangement of the riffles is another important feature of the present invention. The individual riffle plates are each composed of a row of alternately disposed upstanding rectangular lugs or plates and similarly shaped openings or cut away places. The riffle plates are arranged on the surface of the table in such manner as to provide a staggered relation of these plates and cut out portions transversely across the table. The riffle plates in addition to tapering gradually downwardly from the head to the tail of the table, also taper downwardly from the front to the back of the table. By use of these cut out staggered riffle plates tapering in two directions the concentrates are forced to move in a back and forth, zigzag path across the face of the table, the values being collected at the lower, outer edge thereof.

With these and other objects in view the invention consists in the combination and arrangement of parts, more fully set forth in the following specification, illustrated in the accompanying drawing and more particularly pointed out in the appended claims.

In the drawings:—

Figure 1 is a top plan view of a concentrator having one embodiment of the present invention incorporated therein.

Fig. 2 is a transverse sectional view taken on the line 2—2 of Fig. 1, drawn to a larger scale.

Fig. 3 is a side elevation of one of the small riffle plates.

Fig. 4 is a similar view of one of the large riffle plates.

Fig. 5 is an enlarged detail, partly in section, partly in elevation of the adjustable mounting for one of the agitators.

Fig. 6 is a similar view to Fig. 5, taken at right angles thereto.

Fig. 7 is a fragmental plan view drawn to a larger scale of the table, illustrating the riffles, agitators and like parts, and

Fig. 8 is a detail.

Referring now to the drawings, the concentrator is supported in a rectangular frame structure 5. The table 6 is pivotally mounted upon adjustable brackets 8 which latter are pivotally carried by upstanding brackets 9 secured to a suitable base block 110

10. The bracket 8 as shown in Fig. 2 is adapted to be clamped in any fixed position in relation to the supporting bracket 9 by means of a screw threaded rod 11 and clamping nuts 12 carried thereon. Each bracket 8 is provided with a pair of connecting plates 13, the opposite ends of which have ball and socket connections with securing plates 14 carried at the under side of the table and 10 two arms 15 of the bracket 8 respectively. The table is normally positioned so as to incline both longitudinally and transversely, *i. e.*, the front longitudinal edge is lower than the rear edge and the tail end is lower 15 than the head end. It will be seen that the table when mounted as hereinbefore described can be easily connected with any suitable head motion device in order to produce a quick back and forth reciprocating 20 or "oscillating" movement as it is frequently termed. The ore is fed from a pipe 16 into the feed box 17 and passes through the distributing means 18 on to the head of the table at its upper longitudinal edge. 25 Wash water is supplied through a pipe 19 to the trough 20 from which it passes through a series of perforations onto the table 6. A tailing box 21 is suitably located at the forward longitudinal edge of the table 30 and sufficiently beneath the same to catch the overflow of the gangue. A similar box 22 is located below the surface of the table and across the concentrates discharge end thereof to receive the concentrates or metal 35 values.

The riffles which form an important feature of the present invention are arranged longitudinally of the table and their ends terminate in echelon forming a diagonal line 40 extending from the rear longitudinal edge of the table at a point near the head end diagonally across to the extreme right hand corner of the table terminating at its forward longitudinal edge. The riffle plates 45 (see Figs. 3 and 4) each comprises a plurality of solid, rectangular portions 24 and alternately arranged cut away portions or openings 25. The riffles are applied to the surface of the table in such manner that the solid and cut away portions of one riffle are staggered in relation to corresponding solid or cut away portions of the adjacent riffles. By this construction it will be seen that as the ore passes from the rear to the forward 55 edge of the table in addition to its back and forth longitudinal movement it is required to thread its way in and out between the openings and projections of the several riffle plates. The riffle plates are further constructed and arranged in such manner that they taper in both directions. Reference to Fig. 4 illustrates how the solid portions 24 of this riffle (which is one of the longer ones) 60 gradually taper from the left hand end to the right hand end. It will be seen that in

Fig. 3 where one of the smaller riffles is illustrated that this same condition obtains and it will also be noted that the solid portions 24 near the upper head end of this riffle are much lower than the corresponding 70 portions of the longer riffles. In this manner it will be seen that the end A of the first riffle illustrated in Fig. 1 and located at the forward edge of the table is higher than any corresponding portion of any riffle on the 75 table and that from this height the riffles greatly incline downwardly toward the concentrates discharge end of the table and also they incline downwardly in a back or transverse direction toward the rear or elevated 80 edge of the table.

A plurality of stationary agitating devices are carried by transversely arranged bars or members 26 shown best in Fig. 1. These members are supported by a pair of parallel 85 rods 27 extending longitudinally above the table and being rigidly secured to the lower ends of sliding bracket plates 28 which are suspended from an upper longitudinal beam 29 of the framework. Each bracket plate 90 28 is provided with vertical adjusting means comprising a screw threaded rod 29' and manipulating handle 30. In this manner the longitudinal rods 27 may be adjusted to assume a position normally parallel with 95 and suitably spaced above the surface of the table 6. The bracket plates 28 are formed with central openings which slidably engage fixed plates secured to the beam 29 by means of bolts passing therethrough. 100 These bolts carry at their outer ends nuts 35. By loosening these nuts the bracket plates 28 may be swung in either direction out of the vertical in order to enable the agitators to be adjusted to correspond with the tilt of the 105 table. The several agitating devices which are carried by the transverse rods 26 each comprise a plurality of prongs 31 the upper ends of which are clamped together and secured within the lower ends or heads of pins 110 33 passing vertically upwardly through the rods 26 and being held in place by nuts 34 threaded on their upper ends. By adjusting the nuts 34 up or down along the bolts 33 the vertical height of the prongs 31 in relation 115 to the table 6 may be varied to accommodate either coarse or fine ore. The prongs 31 are spread apart so as to present a cluster of three fingers. In Fig. 2 these fingers are shown extending downwardly between the 120 riffle plates to within about one-eighth of an inch of the surface of the table. Now, as the table moves rapidly back and forth in its reciprocating or oscillating motion these several agitating fingers are stationary and 125 the ore which is being moved by the impulses of the table is thoroughly agitated and acted upon by means of its constant impact and contact with these various devices. The adjustable feature of the supporting means 130

which carry the agitating devices is absolutely essential in order that the several fingers throughout the entire area of the table may be maintained in operative relation between the riffle plates.

By means of the special construction and arrangement of the riffle plates provided with cut out sections and disposed in staggered relation to each other and also by the use of the fixed agitating devices a much more thorough and effective separation is accomplished within a shorter space of time than could be accomplished by machines of the usual type. These improvements not only have the advantage of greatly increasing the rapidity of the action of the machine but they also give it a larger capacity than machines would possess constructed according to the usual and well known specifications.

Having described my invention what I claim is:

1. A concentrator of the continuous discharge type having a plurality of longitudinally disposed riffle plates each having alternately formed solid and cut away portions, the said plates being disposed with their cut away portions in staggered relation across the surface of the table and a plurality of stationary agitating devices positioned to act on the material between the riffles and arranged in staggered relation.

2. In a concentrator table, a plurality of longitudinally arranged riffle plates each having alternately formed solid and cut away portions, the solid portions being graduated in height from one extremity of the riffle plate to the other and the solid portions of the adjacent riffle plates being graduated in height transversely of the table.

3. The combination with a reciprocating concentrator table providing for the continuous discharge of the concentrates and provided with riffles, of stationary agitating devices bodily and uniformly adjustably positioned above the table and free of attachment thereto, and adapted to act on the material between the riffles.

Copies of this patent may be obtained for five cents each, by addressing the "Commissioner of Patents, Washington, D. C."

4. The combination with a concentrator table, of an agitating device mounted above the said table, means for vertically adjusting said device, and means for imparting an oscillatory adjustment movement thereto, the two movements being independent of each other.

5. The combination with a reciprocating concentrator table mounted in a frame having longitudinally disposed riffles formed thereon, of means for adjustably inclining the table brackets pivotally suspended from the frame, rods movably supported by said brackets, agitating devices carried by the said rods, and means for securing the brackets and rods in a fixed position, whereby the said agitating devices will act upon the material between the riffles.

6. The combination with a reciprocating concentrator table providing for the continuous discharge of the concentrates and provided with riffles, of stationary agitating devices positioned above the table, free of attachment thereto and adapted to act on the material between the riffles.

7. The combination with a reciprocating concentrator table providing for the continuous discharge of the concentrates and provided with riffles, the riffles gradually increasing in height from one end to the other, of stationary agitators positioned above the table, free of attachment thereto and adapted to act on the material between the riffles.

8. A concentrator of the continuous discharge type having a plurality of longitudinally disposed riffle plates each having alternately formed solid and cut away portions, the said plates being disposed with their cut away portions in staggered relation across the surface of the table and a plurality of stationary agitating devices positioned to act on the material between the riffles.

In testimony whereof I affix my signature, in presence of two witnesses.

ALBERT E. FISH.
